(57) **CLAIM**

I claim the ornamental design for a blow dryer, as shown and described.

DESCRIPTION

This application is filed during the pendency of U.S. Design application Ser. No. 29/716,137, filed Dec. 6, 2019, which is also incorporated herein by reference in its entirety.

FIG. 1 is a front perspective view of a blow dryer, showing my new design with a nozzle attached;

FIG. 2 is a rear perspective view thereof;

FIG. 3 is a left side elevational view thereof, the right side being a mirror image;

FIG. 4 is a front elevational view thereof;

FIG. 5 is a rear elevational view thereof;

FIG. 6 is a top plan view thereof; and,

FIG. 7 is a bottom plan view thereof.

The broken lines showing of a nozzle in FIGS. 1-7 are for illustrating unclaimed portions of the claimed design.

The circular broken line showing of a rear inlet in FIGS. 2 and 5 are for illustrating unclaimed boundary of the claimed design.

The broken lines showing of a button on the handle in FIGS. 1, 3, 4 and 7 are for illustrating unclaimed portions of the claimed design.

The broken lines showing of a switch on the handle in FIGS. 2, 3, 5 and 7 are for illustrating unclaimed portions of the claimed design.

The broken lines showing on the bottom of the handle in FIG. 7 are for illustrating unclaimed boundary of the claimed design.

The broken lines showing of a front bezel on the body in FIGS. 1-4, 6 and 7 are for illustrating unclaimed portions of the claimed design.

The broken lines showing contours on the handle in FIGS. 1-5 and 7 are for illustrating unclaimed portions of the claimed design.

The broken lines showing of the handle in FIGS. 1-5 and 7 are for illustrating unclaimed portions of the claimed design.

1 Claim, 7 Drawing Sheets
